UNITED STATES PATENT OFFICE

MATHIAS J. WEBER, OF CHICAGO, ILLINOIS, ASSIGNOR, BY MESNE ASSIGNMENTS, TO
THE HEALTH-O-METER COMPANY, OF CHICAGO, ILLINOIS, A CORPORATION OF
ILLINOIS

DESIGN FOR A PLATFORM SCALE CASING

Application filed October 17, 1932. Serial No. 45,384. Term of patent 14 years.

To all whom it may concern:

Be it known that I, MATHIAS J. WEBER, a citizen of the United States, residing at Chicago, Cook County, Illinois, have invented a new, original, and ornamental Design for a Platform Scale Casing, of which the following is a specification, reference being had to the accompanying drawing, forming part thereof, showing my new design.

Figures 1, 2 and 3 are perspective views of a device embodying the design of my pres-

ent invention, Figures 2 and 3 being on a relatively reduced scale compared with Figure 1.

The invention resides in a platform scale casing, the particular form or shape of the dial being a non-essential and immaterial feature.

I claim:

The ornamental design for a platform scale casing as shown and described.

MATHIAS J. WEBER.
